DESIGN FOR A KNITTED FABRIC

William J. Beniston, Seaford, N. Y., assignor to Julius Kayser & Co., New York, N. Y., a corporation of New York

Application September 26, 1933. Serial No. 49,345

Term of patent 3½ years

To all whom it may concern:

Be it known that I, WILLIAM J. BENISTON, a citizen of the United States of America, residing at Seaford, county of Nassau, State of New York, have invented a new, original, and ornamental Design for a Knitted Fabric, of which the following is a specification, reference being had to the accompanying drawing forming part thereof.

The drawing shows a portion of the fabric having its lower edge turned over showing the rear face.

I claim:

The ornamental design for a knitted fabric as shown and described.

WILLIAM J. BENISTON.
